SLIP

Esther Cadous, Brooklyn, N. Y.

Application November 19, 1940, Serial No. 366,219

4 Claims. (Cl. 2—73)

This invention relates to slips and has for an object to provide a slip having novel and improved characteristics.

Another object is to provide a slip which is neat and pleasing in appearance, possesses body control characteristics and fits closely over a foundation garment.

Another object is to provide a slip of the above type having elastic panels positioned and arranged to permit the slip to be put on or removed without fastenings.

Another object is to attain the above characteristics by the use of a minimum amount of elastic fabric.

A feature of the invention resides in the use of a pair of elastic panels which are arranged at the sides of the slip between the hip and the bust section and are of sufficient extent to provide elasticity suited to enable the slip to be easily put on or removed. A pair of V-shaped elastic panels are positioned in the top of the back adjacent the first mentioned panels for equalizing the pressure over the bust section, to cause the slip to have a neat, form-fitting appearance, and to produce mild support.

Other objects and advantages will become apparent as the nature of the invention is more fully disclosed.

Although the novel features which are believed to be characteristic of this invention are pointed out more particularly in the claims appended hereto, the invention itself will be better understood by referring to the following description, taken in connection with the accompanying drawing in which a specific embodiment thereof has been set forth for purposes of illustration.

In the drawing:

Fig. 1 is a front elevation of a slip embodying the present invention; and

Fig. 2 is a rear elevation thereof.

In the following description and in the claims certain specific terms are used for convenience in referring to various details of the invention. These terms, however, are to be given as broad an interpretation as the state of the art will permit.

Referring to the drawings more in detail, the slip is shown as comprising a skirt portion 10, a front midriff panel 11, a bust section 12 having bust pockets 13, and a back panel 14, all arranged in the usual manner.

In accordance with the present invention, the slip is provided with side elastic panels 15 of one-way stretch material which extend from the back panel 14 around the two sides of the slip to about the center line of the bust pockets 13 where

they are joined to the front panel 11. The panels 15 are of substantial width from the waistline 16 to a point beneath the bust section 12 and taper in width downwardly to a point 18 at the hipline.

The panels 15 are preferably made of thin, open elastic fabric having a substantial ratio of strength and elasticity to weight and are arranged to stretch horizontally. The portions of the panels 15 at the most restricted part of the garment, namely, at the waistline, where the greatest amount of stretch is required to pass the garment over the hips, is made of the greatest width and the elastic panels taper to a point 18 at the hipline where a minimum amount of stretch is required. The width of the panels 15 throughout accordingly corresponds approximately to the amount of stretch which is required at the various portions of the garment.

20 The panels 15 also extend upwardly to a point 20 at about the center of the bust pockets 13. The upwardly extending points 20 provide a sufficient amount of stretch to pull the lower portions of the bust pockets together and to cause 25 the bust section 12 to fit snugly beneath the busts and to exert mild support without introducing wrinkles or puckers in the material of the garment.

20 A pair of V-shaped elastic panels 21 are provided at the back of the slip extending from the top of the back panel 14 along the side edges thereof to a point overlapping the upper portion of the side panels 15. The panels 21 are formed of a similar material to the panels 15 and are 35 likewise arranged to stretch horizontally. The panels 21 serve to equalize the pressure over the bust section 12 and to cause the garment to be form-fitting over the busts.

30 By arranging the panels 21 to overlap the panel 15, a continuous stretchable section is provided from the top of the slip to the hipline on each side of the slip. The entire garment is thus adapted to be pulled on over the hips and, when in position, to be form-fitting without wrinkles or puckers which would leave unsightly bulges.

35 A pair of shoulder straps 22 extend from the bust pockets 13 to the back of the slip and are attached to the back panels 14 at a point adjacent the elastic panels 21. The straps 22 are 45 accordingly anchored at the back to the non-stretchable back panel 14 and serve as an additional support for holding the bust section 12 in place.

50 In the above described garment the elastic panels 15 and 21 on each side of the slip serve

to hold the slip snug and smooth beneath the outer clothing and also eliminate all fastenings which would otherwise be required to permit the slip to pass over the hips. The slip is self-adjusting to conform to the figure and fits so snugly that the appearance of bulkiness is entirely eliminated.

The elastic panels are so arranged that a minimum amount of elastic fabric is required for the above purpose and the width of elastic throughout the slip conforms in general to the amount of stretch which is required at each particular portion thereof. The elastic panels are so arranged that the bust pockets 13 are molded to the figure and produce a mild support. In the event that the slip is worn over a foundation garment or a brassière, the elastic panels serve to hold the slip tightly and smoothly in place over the same.

The V-shaped panels 21 are widest at the top of the slip and thereby provide the maximum amount of stretch at the top of the bust pockets, as required. The lower, pointed portions of the panels 21 being in registration with the upper portion of the panels 15 also provide a maximum amount of stretch of the lower portion of the bust pocket. The panels 21 accordingly assist in properly molding the bust pockets 13.

In the preferred form, the elastic panels 15 and 21 are made similar in appearance and color to the remainder of the slip so that the slip appears to be made of uniform material throughout. The unsightliness of contrasting elastic material is thus avoided. Inasmuch as elastic material of the above type is more expensive than plain fabric, it is desirable to reduce the quantity thereof to a minimum. The panels 15 and 21 have been arranged and designed with this object in view and utilize efficiently the more expensive elastic fabric.

Although a specific embodiment of the invention has been set forth for purposes of illustration, the invention is capable of various uses and suitable changes and modifications may be made therein as will be apparent to a person skilled in the art. The invention is only to be limited in accordance with the scope of the following claims.

What is claimed is:

1. A slip comprising a skirt section, a front midriff panel, a bust section having bust pockets formed therein, and a back panel co-extensive with said front midriff panel and said bust section, a pair of side panels of one-way stretch elastic fabric joined at the sides of the slip to said back panel and joined to said front midriff panel at about the line of the center of said bust pockets, said elastic panels having substantially uniform width from about the waistline of the slip to a point beneath the bust section and being tapered in width from about the waistline to a point at the hip where the slip is of greatest width, whereby the width of said elastic panels is approximately in proportion to the amount of stretch required at the various portions of the slip to enable the slip to pass over the hips and to be contracted to a form fitting shape when in place on the wearer, said panels having points extending upwardly to about the center of said bust pockets for contracting the same to form-fitting position.

2. A slip comprising a skirt section, a front midriff panel, a bust section having bust pockets formed therein, and a back panel co-extensive with said front midriff panel and said bust section, a pair of side panels of one-way stretch elastic fabric joined at the sides of the slip to

said back panel and joined to said front midriff panel at about the line of the center of said bust pockets, said elastic panels having substantially uniform width from about the waistline of the slip to a point beneath the bust section and being tapered in width from about the waistline to a point at the hip where the slip is of greatest width, whereby the width of said elastic panels is approximately in proportion to the amount of stretch required at the various portions of the slip to enable the slip to pass over the hips and to be contracted to a form-fitting shape when in place on the wearer, said panels having points extending upwardly to about the center of said bust pockets for contracting the same to form-fitting position, and a pair of triangular panels of elastic fabric at the upper portion of the back panel, said triangular panels having their wide portions at the top of the slip and having their points extending downwardly to overlap the upper portion of said first mentioned elastic panels, whereby a continuous elastic section is provided from the top of the slip to the hip.

3. A slip comprising a skirt section, a front midriff panel, a bust section having bust pockets formed therein, and a back panel co-extensive with said front midriff panel and said bust section, a pair of side panels of one-way stretch elastic fabric joined at the sides of the slip to said back panel and joined to said front midriff panel at about the line of the center of said bust pockets, said elastic panels having substantially uniform width from about the waistline of the slip to a point beneath the bust section and being tapered in width from about the waistline to a point at the hip where the slip is of greatest width, whereby the width of said elastic panels is approximately in proportion to the amount of stretch required at the various portions of the slip to enable the slip to pass over the hips and to be contracted to a form-fitting shape when in place on the wearer, said panels having points extending upwardly to about the center of said bust pockets for contracting the same to form-fitting position, a pair of triangular panels of elastic fabric at the upper portion of the back panel, said triangular panels having their wide portions at the top of the slip and having their points extending downwardly to overlap the upper portion of said first mentioned elastic panels, whereby a continuous elastic section is provided from the top of the slip to the hip, and shoulder straps extending from the top of said bust section to the top of the back panel at points adjacent said triangular panels of elastic fabric to provide a firm support for the bust section.

4. A slip comprising a skirt section, a front midriff panel, a bust section having bust pockets formed therein, and a back panel co-extensive with said front midriff panel and said bust section, a pair of side panels of one-way stretch elastic fabric joined at the sides of the slip to said back panel and joined to said front midriff panel at about the line of the center of said bust pockets, said elastic panels having substantially uniform width from about the waistline of the slip to a point beneath the bust section and being tapered in width from about the waistline to a point at the hip where the slip is of greatest width, whereby the width of said elastic panels is approximately in proportion to the amount of stretch required at the various portions of the slip to enable the slip to pass over the hips and to be contracted to a form-fitting shape when in place on the wearer, said panels having points

extending upwardly to about the center of said bust pockets for contracting the same to form-fitting position, a pair of triangular panels of elastic fabric at the upper portion of the back panel, said triangular panels having their wide portions at the top of the slip and having their points extending downwardly to overlap the upper portion of said first mentioned elastic panels, whereby a continuous elastic section is provided

from the top of the slip to the hipline, and shoulder straps extending from the top of said bust section to the top of the back panel at points adjacent said triangular panels of elastic fabric to provide a firm support for the bust section, said elastic fabric corresponding in color and appearance to the remainder of the slip whereby the appearance of a full fabric slip is obtained.

ESTHER CADOUS.
